UNITED STATES PATENT OFFICE.

MILLARD F. FIELD, OF WINTHROP, MASSACHUSETTS, ASSIGNOR TO BARBER-COLMAN COMPANY, OF ROCKFORD, ILLINOIS, A CORPORATION OF ILLINOIS.

MACHINE FOR OPERATING UPON WARPS.

1,383,712.

Specification of Letters Patent. Patented July 5, 1921.

Original application filed June 23, 1898, Serial No. 684,201. Divided and this application filed October 11, 1920. Serial No. 416,120.

To all whom it may concern:

Be it known that I, MILLARD F. FIELD, a citizen of the United States, residing at Winthrop, in the county of Suffolk and 5 Commonwealth of Massachusetts, have invented certain new and useful Improvements in Machines for Operating Upon Warps, of which the following is a specification.

This application is a division of my application Serial No. 684,201, filed June 23, 10 1898.

The invention claimed in the present application relates to improvements in warp-supporting frames, and in its broader aspects is applicable to various types of machines for operating upon warps, as, for example, warp-drawing machines, warp-leasing machines and warp-uniting machines.

In the accompanying drawings, Figure 1 is a vertical cross-sectional view of a warp-drawing machine embodying my invention. Fig. 2 is a rear view of the same, some parts not directly concerned with my invention being omitted, and portions in the center of 25 the machine being shown as broken away to shorten the view. Fig. 3 is a view of parts shown in Fig. 2, drawn to a somewhat enlarged scale, the view being taken on the dotted line 3—3 of Fig. 2. Fig. 4 is a perspective view of the feed screw, showing the course of the warp threads and the manner in which they are acted upon and controlled.

In the drawings, *a* designates the frame of the machine which supports the tracks 30 *b* upon which the mechanism carriage *c* travels.

k is the screw shaft and *l* is the thread-spacing screw on the shaft, the said screw consisting of the frusto-conical and fluted 40 or corrugated part 2 for gradually increasing the tension upon the warp threads as they approach the drawing-in line, and the plain cylindrical part 3 upon which the stretched warp threads may be collected to 45 be taken by the screw part 4.

w are the warp threads which extend up from the warp beam (not shown), and pass between the clamp bars *p*, thence partially around the screw shaft and screw, and thence 50 between the pair of clamp bars *q*. The latter pair of clamp bars hold the ends of the warp threads frictionally but with a yielding pressure so that the same can be drawn out from between the bars without

danger of breaking the threads, while the 55 pair of clamp bars *p* hold the thread so firmly that they cannot be drawn from clamped position between them.

Each pair of clamp bars *p* *q* is connected with a section of their carrying frame *o*, 60 which is so hung or supported that it can move to a limited extent, with the clamp bars, on a line longitudinally of the latter. In the present case the frame *o* is supported or hung from journal pins or rods *r* extending horizontally from each end of the frame, which pins run on rollers *s* journaled in a 65 stationary part of the machine frame.

A strap *t* connected at one end of the clamp bar supporting frame *o*, passing over 70 a pulley *u* and having weights *v* applied to the other end, tends to move the said frame *o* and the clamp bars *p* *q* carried by it and as a matter of course the warp threads engaged by the clamp bars, in the direction of 75 or toward the feed screw *l*.

o' designates a head connected and moving with the carriage *c* and which is provided with a bearing *k'* for supporting the end of the screw rod *k*. From the head *o'* 80 there projects an arm *w* the angular end *w'* of which extends inward in front of the foremost warp threads.

It is desirable that the tension of the warp threads should be even, and this can best be 85 brought about when the length of the warp threads between the two pairs of clamping bars *p* *q* is even and under the same tension when not affected by other things between the holding or clamping points. To secure 90 this evenness in the length of the portion of warp threads in question, when a warp is put into the machine, I may employ various means, that herein shown consisting of 95 making the frame sections which support the clamping bars so that one may be adjusted toward and away from the other. The clamping bars *p* are connected with the frame section *z* which is arranged to be adjustable up and down on the stationary frame *z'* by means of a pinion *a'* on the shaft *b'* adapted to be rotated by an end wheel *c'* or other means on the said shaft, the said pinion engaging a rack *z'* formed on the frame section *z*. The clamping bars *q* are 100 supported on the fixed frame-section *z'*.

The warp threads may be engaged by the clamping bars when the said warp threads

are in the dresser or slasher and they may be thence to the second clamp, spring means engaged so as to make the portions of the tending to swing the second clamp away warp threads between the clamps of uniform length; but to make certain of this result, 65
 5 when the warp is put in the warp-drawing machine the clamping bars p shall be adjusted so that the said portion of warp threads between the clamps will be slack. Then, by turning the hand wheel c' in the 10 proper direction, the section z of the frame o will be moved down with the result of stretching the threads evenly between the two pairs of clamping bars. When this has been done the frame section z may be rigidly 15 secured to the section z^2 by any suitable means.

As is herein represented, the clamping bars q are supported on swinging arms q^2 mounted on a pivot rod q^3 supported in the frame 20 section z^2 . A spring q^4 coiled around said rod operates upon one of the arms q^2 to press it downward until stopped by the stops q^5 on said arms coming into contact with a cross-bar q^6 of the frame section z^2 . (See 25 Fig. 3.) With this construction the weight of the bars q can be made to draw constantly upon the warp threads to assist in keeping them under even tension.

30 It will be understood that the clamp bars q and the connected head carrying the warp-thread separating device (in this case the warp-separating screw l and the arm x) can be carried on a carriage independent of 35 another carriage carrying the clamp bars p , or both clamps can be carried on one carriage as shown in the drawings hereto annexed.

Having thus explained the nature of the 40 invention and described a way of constructing and using the same, though without attempting to state all of the forms in which it may be made or all of the modes of its use, it is declared that what is claimed is:

45 1. In a machine for operating upon warps, a warp support comprising two frame-sections, a clamp on one frame-section to hold warp threads tightly, a clamp on the other frame-section to hold the warp threads 50 loosely, and a shaft extending parallel with the clamps, the threads extending over said shaft, said frame-sections being relatively movable to separate the clamps and thus tension the threads.

55 2. A machine for operating upon warps having, in combination, a frame, a warp clamp on said frame, a second warp clamp mounted to swing on the frame, a shaft extending parallel with and adjacent to the 60 second clamp, the threads extending from the first clamp, thence over the shaft and

65 from said shaft, and a stop to limit the action of said spring means.

3. A machine for operating upon warps having, in combination, a clamp to hold warp threads tightly, a clamp to hold said threads loosely, a shaft extending parallel to the clamps, the threads extending from the first 70 clamp, thence over the shaft and thence to the second clamp, said clamp holding the thread partially wrapped about the shaft, means to move the tight clamp away from the loose clamp, and means to move the loose 75 clamp away from the shaft.

4. A machine for operating upon warps having, in combination, a clamp to hold a sheet of warp threads tightly, a clamp to hold said threads loosely, a shaft extending parallel to the clamps, the threads extending from the first clamp, thence over the shaft and thence to the second clamp, said clamps holding the threads partially wrapped about the shaft, and means to move the tight clamp 80 away from the loose clamp to tension the threads over said shaft.

5. A machine for operating upon warps having, in combination, a clamp to hold warp threads tightly, a clamp to hold said threads loosely, a shaft extending parallel to the clamps, the threads extending from the first clamp, thence over the shaft and thence to the second clamp, said clamps holding the thread partially wrapped about the shaft, and means to move the loose clamp 95 away from the shaft to place tension on the threads.

6. A machine for operating upon warps having, in combination, a clamp to hold warp threads tightly, a clamp to hold said threads loosely, a shaft extending parallel to the clamps, the threads extending from the first clamp, thence over the shaft and thence to the second clamp, said clamps holding the threads partially wrapped about the shaft, and means to move one of the clamps to tension the threads over said shaft. 100

7. A machine for operating upon warps having, in combination, a clamp to hold warp threads tightly, a clamp to hold said threads loosely, a shaft extending parallel to the clamps, the threads extending from the first clamp, thence over the shaft and thence to the second clamp, said clamps holding the threads partially wrapped about the shaft, and means to place tension upon the threads. 110

In testimony whereof, I have hereunto set 115 my hand.

MILLARD F. FIELD.
